[57] CLAIM

The ornamental design for a digital audio disc player, substantially as shown and described.

DESCRIPTION

FIG. 1 is a top plan view of a digital audio disc player showing our new design;

FIG. 2 is a front elevational view thereof;

FIG. 3 is a left side elevational view thereof;

FIG. 4 is a right side elevational view thereof;

FIG. 5 is a bottom plan view thereof;

FIG. 6 is a rear elevational view thereof;

FIG. 7 is a top, front and right side perspective view thereof;

FIG. 8 is a top, front and right side perspective view thereof, shown with the disc tray in an open position; and

FIG. 9 is a cross sectional view thereof, taken along line 9—9 of FIG. 1.

FIG. 1

FIG. 2

FIG. 3

FIG. 4

FIG. 5

FIG. 6
